UNITED STATES PATENT OFFICE.

HOWARD PARKER, OF NASHUA, NEW HAMPSHIRE, ASSIGNOR TO THE IMPROVED PAPER MACHINERY COMPANY, OF NASHUA, NEW HAMPSHIRE, A CORPORATION OF MAINE.

ROLL.

1,100,090.

Specification of Letters Patent.

Patented June 16, 1914.

Application filed June 17, 1909, Serial No. 502,732. Renewed February 7, 1913. Serial No. 746,923.

To all whom it may concern:

Be it known that I, HOWARD PARKER, a citizen of the United States, and a resident of Nashua, in the county of Hillsboro 5 and State of New Hampshire, have invented certain new and useful Improvements in Rolls, of which the following is a specification.

This invention relates to improvements in 10 rolls which may be used for various purposes, the roll illustrated in the drawings being designed for use as a couch roll in paper making and pulp treating machinery. These rolls usually comprise a rigid core 15 and have a surface applied to them either of rubber, felt or some such material.

In the drawings—Figure 1 is a side view partly in section of a roll embodying my invention. Fig. 2 is a transverse section of 20 the same. Fig. 3 is a detail view showing a core construction. Fig. 4 is a detail perspective view on enlarged scale of a section of felt. Fig. 5 is a detail side view of a 25 modification with parts broken away to show construction. Fig. 6 is a detail perspective view on enlarged scale of another modification.

In the embodiment of the invention illustrated in Figs. 1 to 4, *a* denotes the core of 30 the roll. I secure to this core strips of lagging *a'* which are spaced at suitable intervals about the core and extend lengthwise thereof, giving the effect of a longitudinally grooved core. On top of this lagging I wind 35 spirally a strip of felt *b* on edge. I slit this strip to any desired depth but not sufficiently to sever it, as indicated at *c*. In this slit I lay a binding wire *d* which binds the felt onto the core. At intervals I may use a 40 small staple *e* which shall straddle the wire and be driven down into the lagging strips. This winding of felt is compacted endwise on the roll so as to give the roll a full and firm surface. If necessary the surface of 45 the roll can be turned off to make it smooth and of uniform diameter throughout. The slitting of the felt not only provides a means for binding it into place on the roll but also provides a water-way into which the water 50 which is pressed out of the pulp may escape and be led to the end of the roll; the water can also seep down between the strips and pass out through the troughs on the core formed by the lagging strips.

If desired in place of winding a strip of 55 felt or like material onto the roll a single piece of felt *x* having a width equal to the length of the roll may be wrapped about the roll and secured in place and then this sheet may be slit spirally throughout part of its 60 depth as at *x'* and a binding wire laid in to secure the sheet to the roll and separate the divided portions of the sheet to form spiral escape passages for the water and air, with the wire seated at the bottom thereof. 65

In the modified form of the invention shown in Fig. 5 it is desirable to start the winding at the center and have it run toward each end as in that case it makes a shorter travel for the water to get to the end of the 70 roll.

Still another modification is illustrated in Fig. 6, in which a strip of felt *y* is wound spirally about the roll, the binding wire being laid along the center of the strip and the 75 strip being then folded up to present the edges of the strip to form the surface of the roll.

It is apparent that other materials than 80 felt, for instance rubber, could be used in the same way and to the same advantage as is the felt. It is further apparent that the character of the core is not a material part of the invention; it may be a solid core or hollow or of other construction. 85

I claim:

1. A roll comprising a core, a covering wrapped about said core, a spirally arranged slit in said covering, and means located in the bottom of said slit for securing said covering onto said core, substantially as described. 90

2. A roll comprising a core, a strip of covering material wound spirally about said core, said strip being slit for part of its 95 depth, and means located in the bottom of said slit for securing said covering to said core.

3. A roll comprising a core, a covering wrapped about said core, spirally arranged 100 slits in said covering, a binding wire located in the bottom of said slits for binding said cover onto said core, substantially as described.

4. A roll comprising a core, a covering wrapped about said core, spirally arranged slits in said covering, a binding wire located 105 in the bottom of said slits for binding said

2
cover onto said core, and staples straddling said wire and adapted to be driven into said core.

5. A roll comprising a core, a strip of covering material wound spirally about said core, and passages formed between said core and the bottom of said cover and extending lengthwise of said core.

10. A roll comprising a core, lagging strips secured thereto and extending lengthwise thereof, and a strip of covering material wound spirally about said core on said lagging strips.

15. A roll comprising a core, lagging strips secured thereto and extending lengthwise thereof, a strip of covering material wound spirally about said core on said lagging

strips, said strip being slit for part of its depth, and means located in said strip for securing said covering material to said core. 20

8. A roll comprising a core, lagging strips secured thereto and extending lengthwise thereof, a strip of covering material wound spirally about said core on said lagging strips, said strip being slit for part of its depth, a binding wire located in said slits, and staples straddling said binding wire and adapted to be driven into said lagging strips. 25

HOWARD PARKER.
